UNITED STATES PATENT OFFICE.

JOHN T. QUIGLEY, OF BOSTON, MASSACHUSETTS, ASSIGNOR TO COSTMETER COMPANY, OF BOSTON, MASSACHUSETTS, A CORPORATION OF MASSACHUSETTS.

FILING AND INDEXING EQUIPMENT.

1,387,310.

Specification of Letters Patent.

Patented Aug. 9, 1921.

Application filed June 5, 1919. Serial No. 301,886.

To all whom it may concern:

Be it known that I, JOHN T. QUIGLEY, a citizen of the United States, and a resident of Boston, county of Suffolk, and State of Massachusetts, have invented an Improvement in Filing and Indexing Equipments, of which the following description, in connection with the accompanying drawings, is a specification, like characters on the drawings representing like parts.

This invention relates to filing and indexing equipments of the class in which the sheets are arranged with their identification-receiving margins in overlapping relationship, and the invention aims to facilitate the removal of the sheet-holders from and their replacement in their mounting.

My invention will be best understood by reference to the following description, when taken in connection with the accompanying drawings of one specific filing and indexing equipment selected for exemplification, while its scope will be more particularly pointed out in the appended claims.

25 In the drawings:

Figure 1 is a front elevation of a filing and indexing equipment embodying my invention, showing the sheets and sheet-holders in the positions which they normally occupy;

Fig. 2 is a front elevation of a portion of the equipment showing the same arranged preparatory to the removal of the selected sheet and sheet-holder from the mounting;

35 Fig. 3 is a sectional view on line 3—3 of Fig. 2;

Fig. 4 is a sectional view on line 4—4 of Fig. 2;

Fig. 5 is an elevation of one of the sheets 40 and its sheet-holder, illustrating the manner of detaching one from the other; and

Fig. 6 is a plan of one end of a sheet-holder illustrating the notch therein.

Referring to the drawings, and to the embodiment of my invention which is illustrated therein, I have chosen for exemplification a filing and indexing equipment comprising a plurality of sheets 10, arranged with their identification-receiving margins in overlapping relationship, as shown in Fig. 1, each of said sheets being suitably held in a sheet-holder which may be of any appropriate character, but herein comprises a cylindrical tube 11, provided with a longitudinal slot 12 (see Fig. 3), in which the

sheet is received, said sheet being suitably held therein as by a wire 13 (see Fig. 5), which is received within the tube and extends through perforations 14 provided in the sheet. My invention, however, is by no means limited to a sheet-holder of this form.

Herein, the sheet-holder is extended at both ends beyond the edges of the sheet to form trunnions which are received in suitable guides, in which the sheet-holder is mounted to turn about its axis, in an appropriate mounting, herein in the form of a plate 15 whose marginal portions are bent to form inwardly-turned flanges 16 and 17, forming opposed channels 18 and 19, best shown in Fig. 4. The sheet-holders maintain the identification-receiving margins of the sheets in appropriately-spaced relationship, while permitting the sheets and sheet-holders to be swung about their respective axes thereby to present either face of each sheet to view. This is well illustrated in Fig. 3, in which some of the sheets are turned in an upward direction and others in a downward direction.

80 In a file or index of this class, it is desirable to rearrange and reclassify the sheets from time to time, and to make renewals and replacements. To this end, I have herein made suitable provision whereby removal of a selected sheet and sheet-holder may be accomplished without the necessity of removing any others, and without shifting any of the sheets and sheet-holders lengthwise of the channels in which the holders are received.

85 The terminal portions of the sheet-holders are normally locked in their guides, owing to the fact that they are overlapped by the inwardly-facing flanges 16 and 17. This is well illustrated in Figs. 1, 2 and 4. When, however, it is desired to remove a given sheet and sheet-holder, the sheets are opened at the desired point like opening the leaves of a book, and the selected sheet at the point of opening is swung to a position substantially perpendicular to the plate 15, as well illustrated in Fig. 3. Suitable provision is made whereby the sheet-holder when in this position is unlocked at one end, herein at the left-hand side thereof. In the present embodiment, the retaining flange 16 is provided with a plurality of V-shaped tongues 20, separated by corresponding V-shaped notches 21, shown in Fig. 2; and the adjacent end of each sheet-holder is provided

with a notch 22 corresponding in shape to the tongues. As a matter of convenience, in the present example, both ends of the sheet-holder are thus notched so that they are 5 reversible, and hence either end may coöperate with the tongues.

Referring now to Fig. 4, it is apparent that by positioning the sheet in a plane substantially perpendicular to the plate 15, the 10 notches 22 are brought into registration with one of the tongues 20, and when thus positioned, the sheet and the sheet-holder may be rocked about the other end of the sheet-holder as a fulcrum into some such position 15 as that shown in dotted lines in Fig. 4. During this movement, the tongue 20 passes through the slot 22, and the sheet-holder is thus unlocked, whereupon it may be withdrawn lengthwise out of the guide at its 20 other end in an obvious manner. The sheet may now be removed from the sheet-holder, and restored to its place therein, or replaced by another, after which the sheet-holder may be reintroduced into the mounting at 25 any desired point by simply reversing the foregoing operation.

It should now be evident that when the sheets and sheet-holder are in place and in their normal positions represented in Fig. 1, 30 the notches in the sheet-holders are out of registration with the described tongues, and hence the latter serve to lock the sheet-holders in place. Suitable upper and lower limiting stops 23 and 24 may be provided 35 to limit the upward and downward movements, respectively, of the uppermost and lowermost sheet-holders, as will be evident from an examination of Fig. 1.

Having thus described one embodiment of 40 my invention, but without limiting myself thereto, what I claim and desire by Letters Patent to secure is:

1. A filing and indexing equipment comprising, in combination, a plurality of sheets 45 having spaced, overlapped margins, a plurality of sheet-holders, and a pair of guides provided with channels in which the ends of said sheet-holders are received and mounted to turn about their respective axes, said 50 sheet-holders and guides having coöperating means normally locking said sheet-holders in said guides but adapted to unlock and permit said sheet-holders to be removed by

rotation about their axes to predetermined positions.

2. A filing and indexing equipment comprising, in combination, a plurality of sheets having spaced, overlapped margins, a plurality of sheet-holders, and a pair of guides having inwardly facing flanges overlapping the ends of said sheet-holders, one of said flanges being notched to permit the removal of a given sheet-holder by withdrawing one end of the latter through such notched flange.

3. A filing and indexing equipment comprising, in combination, a plurality of sheets having spaced, overlapped margins, a plurality of sheet-holders, a pair of guides having inwardly facing flanges overlapping the ends of said sheet-holders, one of said flanges being provided with a plurality of notches to permit the removal of said sheet-holders by withdrawing one set of ends of the latter through the respective notches.

4. A filing and indexing equipment comprising, in combination, a plurality of sheets having spaced overlapped margins, a plurality of sheet-holders provided with notched ends, a pair of guides having inwardly-facing, sheet-holder retaining flanges one of which is provided with a plurality of spaced tongues normally overlying the adjacent ends of said sheet-holders, the notches of said sheet-holders being movable into registration with said tongues, thereby to permit said sheet-holders to be withdrawn.

5. A filing and indexing equipment comprising, in combination, a plurality of sheets having spaced, overlapped margins, a plurality of sheet-holders provided with notched ends, a pair of guides having inwardly-facing, sheet-holder retaining flanges one of which is provided with a plurality of generally V-shaped tongues separated by generally V-shaped notches, said tongues normally overlying the adjacent ends of said sheet-holders and retaining the same in place, and said sheet-holders being mounted to rotate to bring their notches into registration with said tongues, thereby to permit said sheet-holders to be withdrawn.

In testimony whereof, I have signed my name to this specification.

JOHN T. QUIGLEY.
